JAMES SPEAR, OF PHILADELPHIA, PENNSYLVANIA.

Letters Patent No. 89,179, dated April 20, 1869.

STOVE-COLLAR AND DAMPER.

The Schedule referred to in these Letters Patent and making part of the same.

To all whom it may concern:

Be it known that I, JAMES SPEAR, of No. 1116 Market street, Philadelphia, Pennsylvania, have invented a certain new and useful "Stove-Collar and Damper."

The nature of my invention consists in making the damper, collar, and pipe, of cast-iron, and in three pieces, of such a form as to facilitate the construction of the damper, and adapt it as a permanent attachment to the stove.

The stove-pipe damper, as commonly made, is a section of sheet-iron pipe, with holes drilled through for the pivot of the damper. It is fitted with difficulty, and is easily lost in taking down a stove for the summer. Also, the bearing for the pivot of the damper, being only in sheet-iron, is soon worn so loose that the damper is frequently turned by a puff of wind.

By my invention, the damper becomes a permanent part of the stove, avoiding the use of a damper in a section of the stove-pipe.

To enable others skilled in the art to make and use my invention, I will proceed to describe its construction and operation.

Figure 1 shows the section to be attached to the stove.

Figure 2 is the section to be attached to the stove-pipe.

Figure 3 is the damper.

Figure 4 shows the collar and damper complete, as attached to the cylinder.

Figure 5 is another modification of the invention.

The collar A, fig. 1, is cast with an indentation, a^3 , on each side, into which fits the pivot c^2 of the damper.

The flange a^1 is cast on one end of the collar, by which it is riveted to the sheet-iron cylinder D.

A short section of cast-iron, B, fig. 2, is cast with a socket, b^1 , on one end, having similar indentations, a^3 , corresponding with those in collar A.

The other end, b^2 , is fitted to receive the stove-pipe.

The socket b^1 is cast tapering, so that the collar A slips into it without any fitting.

The damper C is cast circular, having a pivot, c^2 , and turn-buckle c^3 , all in one piece.

The pivot c^2 is placed in the groove a^3 of the collar. The section B is then riveted upon the collar A, securing the damper C in its place. The article complete, as shown in fig. 4, is then riveted to the sheet-iron cylinder D.

What I claim as my invention, and desire to secure by Letters Patent, is—

The construction and combination of the three cast-iron pieces, A B C, so as to form a stove-pipe collar and damper, as herein described.
